(57) **CLAIM**

The ornamental design for a chiropractic adjustor apparatus, as shown and described.

DESCRIPTION

FIG. 1 is a perspective view of a chiropractic adjustor apparatus, showing our new design, with the cord portion broken away for ease of illustration.

FIG. 2 is a left side elevational view of the apparatus.

FIG. 3 is a right side elevational view of the apparatus.

FIG. 4 is a top plan view of the apparatus.

FIG. 5 is a bottom plan view of the apparatus.

FIG. 6 is a front elevational view of the apparatus; and,

FIG. 7 is a rear elevational view of the apparatus.
